United States Patent Office.

D. A. MULLANE AND J. O. L. MURRAY, OF NEW ORLEANS, LOUISIANA.

Letters Patent No. 99,460, dated February 1, 1870.

IMPROVED DEVICE FOR HOLDING TOGETHER THE DIFFERENT PARTS OF BUREAUS AND OTHER ARTICLES OF FURNITURE.

The Schedule referred to in these Letters Patent and making part of the same.

We, D. A. MULLANE and J. O. L. MURRAY, of the city of New Orleans, State of Louisiana, have jointly invented a certain Improvement on the Device for Holding Together the Different Parts of Bureaus and other Articles of Furniture, for which Letters Patent were granted to us, October 5, 1869, numbered 95,504, of which said improvement the following is a specification.

Our invention consists in so modifying the form of what we called our "elbow-bracket" in the specification annexed to said patent, as to adapt the device to furniture that is constructed out of very thin material, and hence, which will not allow of the sinking of the plate from which projects what we denominate our "headed pin," below the surface of said material, without so cutting away the wood that there is not thickness enough in what remains under the plates, to hold the screws with which the latter is fastened in its place, our object being to make the device applicable to furniture, no matter how light or thin may be the parts of which it is composed, which we have found by experience, is not the case with respect to our device, as patented.

Description of the Accompanying Drawings.

Figure 1 is a perspective view of our improvement on our "elbow-bracket," in connection with our headed pin, projecting from its pedestal-plate, and our clamping bifurcated key, to hold the parts together, and

Figures 2, 3, and 4, detached views of these three parts.

An inspection of the drawing will show that instead of making the bottom of the section of the bracket, which is secured in its place by means of the headed pin and key, of unbroken continuity on its under sur-

face, or, in other words, in the same plane throughout the whole of this surface, we provide a transverse recess, which exactly fits over the plate from which the headed pin projects, and is just deep enough to bring the two parts outside it down to the plane of the bottom of said plate.

This modification enables us to screw the said plate on the surface of the parts to which it is attached, and, therefore, avoids the necessity of sinking it below the surface, in order to get a bearing beyond its limits, for the bracket, as in the case of our device as patented, and hence, accomplishes our purpose of adapting it as a fastening to furniture in which there is not sufficient thickness of wood to allow of the sinking of said plate below its surface; and beyond this advantage, we have found that the improvement makes a firmer fastening than the device as originally devised by us, chiefly because of the difficulty of making a smooth bottom to the recesses in which the headed pin-plates are inserted or sunk.

For the purpose of pointing out our invention in the manner prescribed by the statute, we denote the elbow-bracket by marking it A, the transverse recess in its lower surface, B, the headed pin, with its pedestal or supporting-plate, C, and the clamping bifurcated key, D.

We claim, as our invention—

Providing the elbow-bracket A with the transverse recess B, as herein described, for the purpose set forth.

D. A. MULLANE.
